UNITED STATES PATENT OFFICE.

LORENZ STOEHR, OF PITTSBURG, PENNSYLVANIA, ASSIGNOR TO MCKEE & BROTHERS, OF SAME PLACE.

DESIGN FOR TABLE GLASSWARE.

Specification forming part of Design No. 7,758, dated September 15, 1874; application filed August 28, 1874.
[Term of Patent 7 years.]

To all whom it may concern:

Be it known that I, LORENZ STOEHR, of Pittsburgh, in the county of Allegheny and in the State of Pennsylvania, have invented certain new and useful Improvements in Design for Table Glassware; and do hereby declare that the following is a full, clear, and exact description thereof, reference being had to the accompanying drawings, and to the letters of reference marked thereon, making a part of this specification.

The nature of my invention consists of an ornamental design for all kinds of table glassware, such as tumblers, sugar-bowls, pitchers, spoon-holders, butter-bowls, celery-glasses, and other articles of glassware, as more fully hereinafter set forth.

Figure 1 represents a sugar-bowl and cover; Fig. 2, a tumbler; Fig. 3, a butter-bowl; and Fig. 4, a cream or other pitcher, all having my design thereon.

Extending around each of the articles named is a series of blocks, *b b*, having two vertical

sides, the tops of each block being formed into a cone, and the bottoms formed into an inverted cone. Above the top of the circle of blocks is formed a ring of convexities, *a*, one convex being for and above each block *b*. Between the conical tops of the blocks and this ring the glass is beveled inward, and between the vertical sides of the blocks the glass is also beveled. Under the bottom of each block is a V-shaped ring, *c*, each inverted cone of the blocks being above a V in this ring, and the space between the ring and blocks being beveled.

What I claim is—

The design *a b c* for table glassware, herein shown and described.

In testimony that I claim the foregoing I have hereunto set my hand this 12th day of August, 1874.

LORENZ STOEHR.
